L. KOOPERSTEIN

SOAP DISPENSING APPARATUS

Filed April 3, 1925

FIG. 1

FIG. 2

Patented Feb. 23, 1926.

1,573,971

UNITED STATES PATENT OFFICE.

LOUIS KOOPERSTEIN, OF NEW YORK, N. Y., ASSIGNOR TO WEST DISINFECTING COMPANY, OF NEW YORK, N. Y., A CORPORATION OF NEW YORK.

SOAP-DISPENSING APPARATUS.

Application filed April 3, 1925. Serial No. 20,345.

To all whom it may concern:

Be it known that I, LOUIS KOOPERSTEIN, a citizen of the United States of America, residing in New York, county and State of New York, have invented certain new and useful Improvements in Soap-Dispensing Apparatus, of which the following is a specification.

The object of the present invention is to provide soap dispensing apparatus of a type in which a measured quantity of the soap is ejected by the pressure of a plunger manually operated, the dispensing stroke being the forward or initial stroke of the plunger, 15 the return stroke of the plunger being idle.

The invention will be understood by reference to the accompanying drawings, in which—

Figure 1 is a sectional elevation showing 20 an apparatus constructed in accordance with the invention;

Figure 2 is an enlarged sectional view of the structure illustrated in the preceding figure, indicating in dotted lines a modification, and

Figure 3 is a sectional detail view on the line 3—3, Figure 2.

Referring to Figure 1 of the drawings, it will be seen that the device comprises 30 a reservoir A for containing liquid soap to be dispensed. This reservoir is supported upon a dispensing valve body or casing B.

The reservoir is provided with an intake 1 closed by a plug 2 which may be threaded 35 in place or held by friction as desired. The base of reservoir A fits within a cup 3 formed upon the upper portion of casing B. Casing B may be formed with a rear extension 4 merging into a bracket 5, the 40 latter being adapted to be secured upon a wall, or other vertical support.

The casing B is formed with two longitudinal chambers 6 and 7, the second chamber being of somewhat greater diameter 45 than the first. Chamber 6 communicates with reservoir A by means of a passageway 8 in the top of the valve casing so that liquid soap may flow by gravity into the said chamber. Immediately in front of

50 passageway 8 is a piston 9 carried at the rear end of a push-rod 10 having a thumb piece 11. Push-rod 10 is guided in its movements by a screw plug 12 formed with a central longitudinal aperture to receive rod 10 and provided with outer threads so that

the plug may be threaded within chamber 7.

Within the casing and at the rear of screw plug 12 is a valve sleeve 13 which is provided with a central aperture to permit passage of the push-rod. Intermediate 60 valve sleeve 13 and piston 9 is a washer 14 of fibre, leather or the like. This washer bears against an annular shoulder 15 in the casing, which shoulder marks the separation point of the two chambers 6 and 7 of unequal diameters. It will be seen that by means of threaded plug 12 sufficient pressure can be placed upon valve sleeve 13 and washer 14 as to hold these members firmly in position within the valve casing. 70

Valve sleeve 13 is formed with a circumferential channel 16, which communicates with a transverse duct 17 leading to the discharge nozzle 18. Rearwardly of piston 19 the push-rod 10 normally closes duct 17. 75 However, at a point slightly in advance of the duct 17, push-rod 10 is provided with a section of reduced diameter, indicated in the drawings by the numeral 10^x. Piston 9 normally seals chamber 6 against the passage of soap to the discharge outlet. When push-rod 10 is moved rearwardly, the piston first closes passageway 8 thus preventing the flow of soap intermediate the reservoir and chamber 6 and then exerts a pressure 80 upon the soap in chamber 6 rearwardly of the piston so that said soap is forced through outlet 19, thence through tube 20.

At this instance of operation, the reduced section 10^x of push-rod 10 will communicate 85 with transverse duct 17 and also with outlet 21 of tube 20 so that the soap theretofore put under pressure by piston 9 will be ejected by passage through the tube over the reduced section of the push-rod through 90 duct 17 and out discharge nozzle 18. In its rearward movement the push-rod is resisted by spring 22 which, when the rod is released, will return the parts to initial position, as 95 illustrated in Figure 2. 100

While in most cases I prefer that the communication between outlet 19 and inlet 20 be effected by means of a tube such as the tube 20 illustrated in the drawings, such tube may be eliminated and the top wall of the casing closed except for the soap passageway 8. This modification is possible when a channel such as that indicated by dotted lines 23, Figures 2 and 3 is formed 110 in chamber 6 at the bottom wall thereof.

The forward end of the channel will be closed in the normal position of the elements and will be opened by the rearward movement of the push-rod and piston, the action being exactly the same as when the tube 20 is employed. This and other modifications are within the spirit of the invention, what I claim and desire to secure by Letters Patent being as follows:—

- 10 1. A soap dispenser having, in combination, a valve body provided with an inlet and an outlet, a piston, a duct extending from opposite sides of the inlet, the outlet end of said duct being normally closed by the piston and means for imparting endwise movement to the piston whereby the inlet is closed and thereafter the outlet is opened, the continued movement of the piston forcing liquid through said duct and into the discharge outlet.
- 15 2. A soap dispenser having, in combination, a valve body formed with an inlet and a discharge outlet, a piston in said body and normally disposed in advance of the inlet, a duct in the valve body and extending from a point rearwardly of the inlet to a point forwardly thereof, and means for imparting endwise movement to the piston, whereby the latter first closes the inlet and then forces liquid through said duct to the discharge outlet.
- 20 3. A liquid dispenser having, in combination, a valve body provided with a longitudinal chamber having an inlet and an outlet, said chamber being provided with

a duct leading from a point rearwardly of the inlet to a point in advance thereof, a packing member, a piston, a spring normally holding the piston in position to close the outlet of the duct and also in engagement with said packing and means for imparting endwise movement to the piston.

4. A liquid dispenser having, in combination, a valve body provided with an inlet and an outlet, a duct leading from a point rearwardly of the inlet to a point forwardly thereof, a piston normally closing the outlet end of the duct and disposed in advance of the inlet, a spring engaging the piston, a push-rod connected to the piston and having an intermediate section of reduced diameter, a valve sleeve surrounding the push-rod and having a duct communicating with the outlet, said duct being normally closed by the wall of the push-rod and a packing intermediate the valve sleeve and the piston.

5. A liquid dispenser having, in combination, a valve body provided with an inlet and an outlet, a tube adapted to convey liquid from a point rearwardly of the inlet to a point in advance thereof, a piston normally closing the outlet end of the tube and disposed in advance of the inlet, a push-rod connected to the piston and having a reduced intermediate section, said piston normally closing the discharge outlet and a spring engaging the piston.

In testimony whereof, I have signed my name to this specification.

LOUIS KOOPERSTEIN.
